(57) **CLAIM**

The ornamental design for a gaming tablet having concealed controls, as shown and described.

DESCRIPTION

FIG. 1 is a left side perspective view of the gaming tablet having concealed controls, showing our new design, with the gaming controls in the open condition;

FIG. 2 is a right side perspective view thereof;

FIG. 3 is a rear perspective view thereof;

FIG. 4 is a bottom perspective view thereof;

FIG. 5 is a top view thereof;

FIG. 6 is a bottom view thereof;

FIG. 7 is a rear view thereof;

FIG. 8 is a front view thereof;

FIG. 9 is a left side view thereof;

FIG. 10 is a right side view thereof;

FIG. 11 is a top perspective view of the gaming tablet having concealed controls, showing my new design, with the gaming controls in the closed condition;

FIG. 12 is a bottom perspective view thereof;

FIG. 13 is a top view thereof;

FIG. 14 is a bottom view thereof;

FIG. 15 is a rear view thereof;

FIG. 16 is a front view thereof;

FIG. 17 is a left side view thereof; and,

FIG. 18 is a right side view thereof.
